(57) **CLAIM**

The ornamental design for a tipping bird water toy as shown and described.

DESCRIPTION

FIG. 1 is a perspective top, front view of a tipping bird water toy of the applicant's design;

FIG. 2 is a perspective bottom, rear view of FIG. 1;

FIG. 3 is a front view of FIG. 1;

FIG. 4 is a left-side view of FIG. 1;

FIG. 5 is a rear view of FIG. 1;

FIG. 6 is a right-side view of FIG. 1;

FIG. 7 is a top view of FIG. 1;

FIG. 8 is a bottom view of FIG. 1; and,

FIG. 9 is a cross-sectional view of FIG. 4 taken along the lines 9-9.

Broken lines are included for the purpose of illustrating portions of the tipping bird water toy that form no part of the claimed design.

The dash-dot-dot-dash lines shown in the drawings define the bounds of the claimed design and form no part thereof.
